[57] CLAIM

The ornamental design for a toy air boat, as shown and described.

DESCRIPTION

FIG. 1 is a front perspective view of a toy air boat showing our new design;

FIG. 2 is a front elevational view thereof shown on a slightly reduced scale;

FIG. 3 is a rear elevational view thereof;

FIG. 4 is a left side elevational view thereof, the side opposite being a mirror image;

FIG. 5 is a top plan view thereof;

FIG. 6 is a bottom plan view thereof;

FIG. 7 is a perspective view of a modified embodiment of the design shown in FIGS. 1 through 6;

FIG. 8 is a front elevational view thereof;

FIG. 9 is a rear elevational view thereof;

FIG. 10 is a front perspective view of a second modified embodiment of the design shown in FIGS. 1 through 6;

FIG. 11 is a front elevational view thereof;

FIG. 12 is a rear elevational view thereof;

FIG. 13 is a left side elevational view thereof, the side opposite being a mirror image; and,

FIG. 14 is a top plan view thereof.

The unshown bottom of the two modified embodiments of the design is identical to what is shown in FIG. 6. The broken line showing of a propeller in FIGS. 7, 8 and 9 represents environment only and forms no part of the claimed design.
